TROLLEY CONDUCTOR DEVICE

Raymond P. Hanna and Leland F. Brahma, Wilkinsburg, Pa., assignors to Westinghouse Electric Corporation, East Pittsburgh, Pa., a corporation of Pennsylvania

Application August 30, 1946, Serial No. 693,934

16 Claims. (Cl. 191—37)

1

Our invention relates, generally, to trolley conductor devices and it has reference in particular to insulated crossing devices for trolley conductors.

Generally stated, it is an object of our invention to provide an improved trolley conductor device that is simple and inexpensive to manufacture and is easy to install.

More specifically, it is an object of our invention to provide an insulated trolley conductor crossing which may be readily installed in connection with continuous trolley conductors.

It is also an important object of our invention to provide for utilizing spaced tension and compression members in an insulated trolley conductor device.

Another object of our invention is to provide a light and durable adjustable trolley conductor crossing.

Yet another object of our invention is to provide an insulated trolley conductor crossing in which spaced tension and compression members of different lengths may be used so as to provide insulated crossings of different lengths.

It is an important object of our invention to provide for using a tubular compression member in an insulated trolley conductor crossing so that one of the conductors may be positioned therein.

Still another object of our invention is to provide for securing an insulated runner member to a trolley conductor device by means of a renewable metallic runner member adjacent thereto.

Another important object of our invention is to provide a detachable approach member having a trolley conductor device which may be arranged in clamped relation with the device and the trolley conductor.

A further object of our invention is to provide a trolley conductor device for attachment to a conductor and having preformed lip portions positioned around the conductor so that no peening operation is necessary after the installation of the device.

It is also an important object of our invention to provide for using a pair of spaced compression members in an insulated trolley conductor device so that the conductor may be positioned therebetween.

It is also a further object of our invention to provide a trolley conductor device having complementary clamp portions positioned on opposite sides of the conductor and arranged to partially enclose the conductor to provide a smooth surface for guiding a current collector therealong.

2

Other objects will in part be obvious, and will in part be explained hereinafter.

In one embodiment of our invention an insulated device having spaced end members connected by vertically spaced tension and compression members, may be used for providing an insulated adjustable crossing. The tension member comprises an insulating member connecting the end members adjacent the normal plane of the trolley conductor. The compression member comprises a suitable length of pipe positioned between the upper ends of the end members and is provided with a longitudinal slot for receiving one of the conductors which is positioned in upwardly inclined openings in the end members. A bearing for a supporting a crossing member is secured to the insulating tension member. Insulated runner members are positioned intermediate the end members and the bearing member by means of renewable runner portions which are secured to the end members. The runner members comprise opposed clamp portions having depending lips which are preformed so as to partially enclose the conductor, and are secured in clamped relation with the conductor to provide a smooth approach for a current collector.

For a more complete understanding of the nature and scope of our invention, reference may be made to the following detailed description, which may be studied in connection with the accompanying drawings in which:

Fig. 1 is a partially broken away plan view of an adjustable insulated crossing embodying the invention in one of its forms;

Fig. 2 is an enlarged partial side elevational view of the crossing shown in Fig. 1, broken away in part;

Fig. 3 is an enlarged sectional view taken along the line III—III of Fig. 2;

Fig. 4 is an enlarged sectional view taken along the line IV—IV of Fig. 2;

Fig. 5 is an enlarged sectional view taken along the line V—V of Fig. 2;

Fig. 6 is an enlarged sectional view taken along the line VI—VI of Fig. 2;

Fig. 7 is a partially sectioned enlarged side elevation view of the bearing support and adjustable crossing member;

Fig. 8 is an enlarged plan view broken away in part of the bearing support and crossing member;

Fig. 9 is an enlarged partial side elevational view of an adjustable crossing showing another modification of the invention;

Fig. 10 is a sectional view taken along the

line X—X of Fig. 9 with a current collector shoe shown in dotted outline.

Fig. 11 is an enlarged partial plan view of an insulated crossing embodying a modification of the invention;

Fig. 12 is an enlarged partial side elevational view of the crossing of Fig. 11; and

Fig. 13 is a sectional view along the line XIII—XIII of Fig. 12.

Referring particularly to Figs. 1 and 2, the reference numeral 10 may denote generally an insulated adjustable trolley conductor crossing device having spaced end members 11 and 12 which are maintained in spaced relation by means of an elongated compression member 14 and insulated tension members 16 and 17 which may be connected between the end members and a bearing support 20 for an adjustable crossing member 21.

The end members 11 and 12, which may be substantially identical, may as shown in Figs. 1 through 4 comprise metallic members having upwardly inclined open conductor channels 22 for receiving a principal continuous trolley conductor (shown only in dotted outline in Figs. 3, 4 and 5), and which terminate in sockets 23 adjacent the upper ends for receiving the compression member 14. A depending web 24 may be provided on the lower side of the end member for positioning a substantially U-shaped renewable runner member 25. The runner member may be provided with upstanding ears 26 at one end and laterally projecting lugs 27 at the other end for securing it to the end member. Means such as the spaced ears 26 may be provided on the end members for cooperating with eye-bolts 29 to connect the tension members 16 thereto. Brackets 30 may be provided on the sides of the end members in association with the lugs 27 of the runner member, and projecting end portions 32 may be provided in association with the ears 26 and a bolt 31 for securing the renewable runner member 27 in operating relation to the end member.

The bearing support 20 may be either secured to a continuous tension member extending between the end members 11 and 12 or may, as shown in Figs. 2, 6, 7 and 8, comprise a central web 33 having clevices 34 and 35 adjacent the ends for effecting connection by means of pins 36 to eye-bolts 29 at the ends of the tension members 16 and 17. Transverse ears 38 may be provided on the web 33 adjacent the clevices 34 and 35 for cooperating with brackets 39 to secure metallic guides or approaches 40 to the bearing support. The guides 40 may each be provided with a recess 41 for receiving reduced extension 42 on one end of the insulating runner member 43, while an overhanging projection 45 may be provided adjacent the other end for securing a circular bearing plate 47 of the crossing member 22 in operating relation to the bearing support 20. The bearing plate 47 may be provided with projecting channeled runner portions 48 for receiving a continuous intersecting trolley conductor and for guiding a current collector across the crossing device. Suitable approach members such as the approach member 49 may be secured to the runner portions 48, being for example, hooked to a clevis wire retaining member 50. An elongated opening 51 may be provided in the web 33 for receiving the intersecting trolley conductor.

In order to provide for a continuous trolley conductor, retaining means may be utilized in

conjunction with the end members 11 and 12 comprising, for example, a depending central web 52 for engaging a trolley conductor to depress it into the conductor channel 22, and a transverse flange 53 for receiving bolts 54 which may be mounted in ears or brackets 55 on opposite sides of the end members. Approach members 49 may also be connected to the crossing device adjacent the ends being, for example, secured by hook members 58 which may be positioned about transverse holding means, such as the bolt 31 which secures the renewable runner member 25 to the end member. As shown in Fig. 5, the compression member 14 may comprise a length of pipe having a central opening 60 for receiving a continuous trolley conductor, and having oppositely threaded end portions threaded into the sockets 23 of the end members. A longitudinal slot 61 may be provided in the compression member 14 for positioning the conductor in the opening 60. A sleeve of insulation 62 may be positioned about the compression member 14, having a slot 63 for positioning the conductor in the opening 60 of the compression member.

In installing the crossing device, the compression member 14 may be rotated in the sockets 23 so that the opening 61 is aligned with the conductor channels 22 in the end members 11 and 12. The principal trolley conductor may then be positioned in the compression member which may then be rotated in the sockets 23 so that the slot 61 is on the lower side, and the upper side presents a solid surface. The conductor may then be depressed in the conductor channels 22 and secured by the retaining means, whereupon the approaches 49 may be installed. The intersecting or crossing trolley conductor may be positioned in the channeled crossing runner members 48 whereupon the crossing member may be positioned against the lower side of the bearing support 20, and secured in operating relation by attaching the approach members 40.

Referring to Figs. 9 and 10, it will be seen that instead of using renewable runner members 27 and approach members 49 in conjunction with the end members 11 and 12, unitary approach and runner members 65 may be provided which may be positioned about both the trolley conductor and the lower portion of the end member 66, which may be substantially identical with the end members 11 and 12, except that the end projections 32 may, if desired, be removed.

The approach 65 may comprise opposed clamping portions 67 and 68 which may be positioned on opposite sides of a trolley conductor and of the depending web 69 of the end member 66, which corresponds to the web 25 of the end members 11 and 12. The opposing portions 67 and 68 of approach 65 may be provided with depending lips 70 and 71 which may be preformed to provide a central opening 72 for receiving a trolley conductor. Means such as the transverse bolt 74 may be provided for effecting clamping engagement of the complementary portions 67 and 68 of the approach with the trolley conductor as well as with the depending web 69 of the end member 66 for securing the approach in operating relation. The depending lips 70 and 71 may be of gradually decreasing depth and thickness adjacent the outer end so as to provide a tapering contact surface 75 for effecting gradual transfer of a current collector from the trolley conductor to the approach.

The complementary portion 67 and 68 may be separated or may be integral at one end being,

for example, separated along the upper sides and joined along the lower side. They may be separated for at least a portion of their length by means of a longitudinal slot 78, so that they may be readily positioned about the trolley conductor. Transverse flanges 79 may be provided adjacent the other ends of the approaches for securing the approach more firmly to the end member in conjunction with lugs 80 on opposite sides of the end members. Recesses 81 may be provided adjacent the inner ends of the approaches for receiving the reduced extensions 82 on the ends of the insulating runner members 43, for securing them in operating relation.

Referring to Figures 11, 12 and 13, it will be seen that in a modification of the invention the adjustable insulated trolley crossing 90 may comprise a crossing member 21 similar to that used in the crossing of Figures 1 through 10, and which may be supported from a continuous insulating tension member 92 which may be connected between spaced metallic end members, such as the end member 93. The end members may be provided with horizontal spaced compression members 94 which may be interposed between the end members above the tension member.

The end member 93 may comprise an upwardly inclined open channel portion 95 having a depending central web 96 on the lower side for positioning a substantially U-shaped runner member 97. The runner member may be secured to the end member by means of upwardly projecting ears 98 and 99 in conjunction with through bolts 100 and 101, respectively. Adjacent their inner ends, the end members 93 may be provided with spaced flanges 103 for receiving the ends of the tension member 92. Means, such as the bolts 104, may be used to secure the tension member between the flanges. Adjacent their other ends, the end member 93 may be provided with wire retaining means comprising a transverse flange 105 for securing the retaining means to the end member and a depending central web 106 for depressing a continuous trolley conductor into the channel 95. A clevis 107 may be provided on the wire retaining means for engaging hook means 108 on a detachable approach member 109 for providing a smooth approach for a current collector.

In order to support the crossing member 21, means, such as the bearing support members 110, may be secured to the tension member 92 intermediate its ends. The bearing support members may, for example, comprise plate portions 112 which may be secured to the tension member by means of bolts 113 and angularly related bearing portions 115 which project laterally to provide a guide for the channel-shaped runner portions 48 of the crossing member 21. The crossing member may be retained in operating relation with the bearing members 110 by means of detachable guide members 117 which may be detachably secured to the tension member 92 by means of upwardly projecting ears 118 and through bolts 119. Insulated runners 120 may be positioned along the lower side of the tension member 92 being, for example, positioned by means of end projections 121 which may be engaged by the removable runner member 97 and the guide member 117. A channel shaped insulating member 123 may be secured along the upper side of the tension member 92 for receiving a continuous trolley conductor (not shown) so as to isolate it from the bearing support members 110.

Instead of using a single compression member

between the end members 93, a pair of horizontally shaped compression members 94 may be used, so as to provide for running a continuous trolley conductor along the top of the tension member 92 in the space between the compression members. The compression members 94 may, for example, comprise suitable lengths of pipe having a layer of insulating material 126 positioned thereon. The compression members 94 may be positioned between the end members 93, by securing them to transverse brackets 127 which project laterally from the end members adjacent the upper edge. Bolts 128 may be used to secure the compression members 94 to the brackets 127.

From the above described construction and the accompanying drawings, it will be apparent that we have provided an insulated adjustable crossing which is simple and inexpensive to manufacture and is easy to install. By utilizing a construction embodying spaced tension and compression members, insulated crossings of many different lengths may be readily provided since only the tension and compression members need be of different length for different lengths of crossing devices. This construction, therefore, provides an extremely flexible design which may be readily adapted to numerous operating conditions. By providing for positioning the trolley conductors in the manner described, installation of the crossing device is greatly facilitated, and a light weight yet mechanically strong construction is provided. By utilizing approach members of the clamp type, a smooth approach may be provided without requiring a peening operation after the approach has been installed as is the case with the usual type of approach. This means that the preformed lip construction provides extremely smooth contact surface which affords a minimum of abrasion to current collectors, and greatly increases the operating life of collector devices, particularly those of the carbon shoe type which are especially affected by abrupt or rough surfaces.

Since certain changes may be made in the above described construction, and different embodiments of the invention may be made without departing from the spirit or scope thereof, it is intended that all of the matter contained in the above description and shown in the accompanying drawings, shall be considered as illustrative and not in a limiting sense.

We claim as our invention:

1. In a trolley conductor device, a pair of spaced end members having means for securing a continuous conductor and raising it above a normal level intermediate said members, spaced tension and compression members connecting the end members adjacent the normal level of the conductor and adjacent the ends of the end members remote from the normal conductor level, respectively, the compression member having its longitudinal axis above the raised portion of the trolley conductor and an insulating runner positioned between the end members to guide a current collector.

2. A trolley conductor device for use with a continuous conductor comprising, a pair of spaced end members having upwardly inclined open channels to receive the conductor, tension means connecting the end members adjacent the normal level of the conductor, an insulated runner positioned between the end members in substantially the normal conductor level, and a compression member interposed between the end members above the tension member having a re-

cess to receive the conductor and position it below the longitudinal axis of the compression member.

3. A trolley conductor device comprising, a pair of spaced apart metallic end members having upwardly inclined open channels for receiving a continuous trolley conductor and terminating in sockets above the normal level of the conductor, an insulating tension member connected between the end members relatively close to the normal level of the conductor, insulating runner means extending between the end members in substantially the normal level of the conductor, and a tubular compression member having end portions rotatably positioned in the sockets of the end members and provided with a longitudinal slot in one side to receive the trolley conductor.

4. In an insulator device for a continuous trolley conductor, a pair of spaced apart end members having upwardly inclined open channels on their remote edges to receive the conductor and oppositely threaded sockets at the upper ends of the channels on the adjacent edges, means securing the conductor in said channels, an insulated tension member connecting the end members adjacent the normal level of the conductor, insulated runner means positioned below the tension member in substantially the normal level of the conductor, and a tubular tension member having oppositely threaded end portions fitting in said sockets and having an opening in one side to receive the conductor.

5. An insulator device comprising, spaced end members having upwardly sloping open channels on the remote edges terminating in sockets at the upper ends of the adjacent sides, a tubular compression member extending between the sockets and having an opening in one side to receive a continuous conductor, insulating means rotatably positioned on the compression member and provided with a longitudinal conductor slot, insulating tension means connecting the end members intermediate the compression member and the normal level of the conductor, and insulating runner means positioned between the end members in substantially the normal level of the conductor.

6. An insulated crossing comprising, a pair of spaced apart end members, a support for a crossing member, tension means pivotally connected between the end members and the support to position the support intermediate the end members, compression means interposed between the end members above and in spaced relation to the tension means and support, and insulating runner means interposed between the support and the end members beneath the tension means.

7. In an insulated crossing, in combination, a pair of spaced apart metallic end members having upwardly inclined open channels to receive a continuous conductor, compression means interposed between the end members above the normal level of the conductor, insulating support means disposed to position the conductor below the longitudinal axis of the compression means, said support means having a recess arranged to receive the conductor, means depressing the conductor in the open channels, a support for a crossing member position intermediate the end members, tension means connecting the support to the end members adjacent the normal level of the conductor, and runner members positioned intermediate the end members and the support

in substantially the normal level of the conductor.

8. An insulated crossing comprising, a pair of metallic end members having runner portions along the lower edge to guide a current collector and having upwardly inclined open channels to receive a conductor terminating in sockets adjacent the upper end of adjacent edges, a tubular compression member extending between the sockets and having a slot on one side to receive the conductor, a tubular insulating member rotatably positioned about the compression member and provided with a slot to receive the conductor, a support for a crossing member, tension means connecting the end members intermediate the compression member and the normal level of the conductor and positioning the crossing support intermediate the end members, and insulated runner members interposed between the end members and the crossing support in substantially the normal level of the conductor.

9. A trolley conductor device comprising, end means secured to a trolley conductor and arranged to elevate the conductor above its normal level for a predetermined distance, tension and compression members connecting the end means in vertically spaced relation, insulating means arranged to position the trolley conductor intermediate the tension and compression members for a portion of said distance, and runner means positioned intermediate the end means of the device operable to guide a circuit collector along the device.

10. In a trolley conductor device having spaced end members for raising a continuous conductor above its normal level for a predetermined distance, longitudinal tension and compression means connecting the end members and disposed vertically of each other, channel means intermediate said means to position the conductor, insulating runner means positioned beneath the tension means to guide a current collector, and elongated renewable runner members extending along the lower edges of the end members arranged to secure the insulating runner means to the device.

11. A trolley conductor device comprising, spaced end members, insulating runner means extending between the end members, and means securing the insulating runner means including longitudinally split elongated runner means positioned in clamping relation about the conductor and lower edges of the end members.

12. A renewable approach member for use with a trolley conductor device comprising, a pair of opposed sections having depending lips defining a central groove for a trolley conductor, said lips being of gradually less depth toward the end remote from the device, and adjustable clamping means operable to effect clamping engagement of said sections to clamp the conductor and an integral end portion of said device between said sections.

13. An approach device for use with a round trolley conductor and a trolley conductor device comprising, elongated opposed body portions disposed to be positioned on opposite sides of a portion of the trolley conductor device and having depending inwardly turned lips defining a central groove for the conductor, said lips being of gradually decreasing depth and thickness toward the ends of the body portions, and transverse means operable to effect clamping engagement of the sections with the conductor and the por-

tion of the trolley conductor device positioned therebetween.

14. A trolley conductor device comprising, spaced end members, an elongated tension member connecting the end members adjacent their lower sides, a pair of horizontally spaced compression members positioned between the end members adjacent their upper sides, and insulating means intermediate the end members to position a trolley conductor between the longitudinal axes of the tension and compression members. 10

15. A trolley conductor device comprising, a pair of spaced end members for attachment to a trolley conductor, an elongated tension member of insulating material connected between the end members adjacent the normal plane of the conductor, means secured to the tension member intermediate its ends for supporting a crossing member, a pair of horizontally spaced compression members connected between the end members above the longitudinal axis of the tension member, and a channel member intermediate the tension member and compression members to receive the trolley conductor. 15

16. An insulated trolley crossing comprising, 20 a pair of spaced end members having upwardly

inclined channels for positioning a trolley conductor and spaced longitudinal flanges on adjacent ends with transverse webs adjacent the upper edges, an insulating tension member connected between the spaced flanges, compression members connected between the transverse webs, support means for a crossing member connected to the tension member intermediate its ends, and insulating means on the tension member for receiving the trolley conductor to insulate it from the crossing member support means. 10
